UNITED STATES PATENT OFFICE.

WILLIAM A. CHRYSST, OF DAYTON, OHIO, ASSIGNOR TO THE DAYTON ENGINEERING LABORATORIES COMPANY, A CORPORATION OF OHIO.

ENGINE STARTING SYSTEM.

1,306,137.

Specification of Letters Patent. Patented June 10, 1919.

Original application filed September 30, 1915, Serial No. 53,264. Divided and this application filed July 16, 1917. Serial No. 180,836.

To all whom it may concern:

Be it known that I, WILLIAM A. CHRYSST, a citizen of the United States of America, residing at Dayton, county of Montgomery, 5 and State of Ohio, have invented certain new and useful Improvements in Engine Starting Systems, of which the following is a full, clear, and exact description.

This invention relates to improvements 10 in starting systems for internal combustion or explosion engines, and more particularly to that type of system which is adaptable for use with engines capable of operating either in a forward or reverse 15 direction.

One of the objects of the present invention is to provide a starting system in combination with a reversible engine, which may be so coupled up to said engine as to 20 crank the engine in either a forward or reverse direction, in accordance with the direction in which it is desired to have the engine run, after it has once been started.

One manner of attaining the above object may be by providing two prime movers, one of which being capable of operation in one direction while the other is capable of operation in the opposite direction, and also providing a plurality of connecting units 25 or devices which may be actuated to couple up either one or the other of said prime movers to the engine, so as to operate the engine in either a forward or reverse direction.

35 In combination with the above mentioned prime movers and their respective connecting units, there is provided a controlling element, having a plurality of operative positions, so that when said controlling element is moved to one of its operative positions, one of said prime movers will be connected to the engine by means of one of the connecting units, to turn said engine in one direction.

45 The functions of this controlling element, when moved to another of its operative positions, is substantially the same with respect to another prime mover. The result of the above arrangement and construction 50 is that when one of the prime movers is brought into operation, the engine may be cranked in one direction, while when another of the prime movers is brought into

operation, the engine will be cranked in an opposite direction.

The present application is a division of my co-pending application, filed September 30, 1915, Serial No. 53,264.

In the present form of the invention, the starting device includes separate motors, 60 one of which is mounted on each side of the engine, so that this connecting device may be readily shifted to couple up that particular motor to the engine, to crank the engine in one direction, while when it is desired to crank the engine in an opposite direction, another cranking device will be shifted into position to couple another motor with the engine, whereby the engine will be cranked in an opposite direction.

By referring to the drawing, the starting device or system includes two separate prime movers or electric motors, designated by the numerals 120 and 121, one of which is mounted on each side of the engine.

In the present invention, a single source of current is employed as at 122, and has suitable circuit connections with the respective motors, as will be described herein-after.

The main operating or controlling member 123 is suitably mounted in such a manner that it may be moved to a plurality of operative positions, in any one of which positions the circuit connections between 85 the source 122 and one of the motors will be closed concomitantly with the completion of the shifting of one of the connecting units.

By referring to the drawing, the operation of the system will be described when the same is brought into operation by the shifting of the controlling member into the extreme right-hand position.

Upon the initial movement of this controlling member, the connecting unit 124 will be moved toward the flywheel 125, and concomitantly an initial movement will be imparted to the motor 120 by the closing of the following circuit, through the effect 90 of a bridging element 126, carried by the controlling member 123: from the battery 122, conductors 127 and 128, through the series field winding 129, across the brushes of the motor 120, through conductor 130 100 to the common terminal 131, across the

bridging element 126 to the terminal 132, through resistance unit 133, and back to the opposite side of the battery, via conductor 134.

5 The object of imparting an initial movement to the motor, is simply to facilitate in the connecting up of the pinion of the connecting unit with the flywheel gearing.

Now, as soon as the pinion 124 has been 10 brought into enmeshment with the flywheel gearing a determined degree, the controlling member 123 will be moved into position to close the following circuit, which may be designated the main cranking motor circuit: 15 from the battery 122, conductors 127 and 128, through series field winding 129, across the brushes of the motor 120 to lead wire 130, common terminal 131, through the bridging element 126 to the terminal 135 20 and thence back to the battery, via conductor 134. When the engine has become self-operative, the controlling member 123 may be released, and the spring 136 will effect the unmeshing movement of gear 124, 25 and will restore the member 123 to inoperative position.

If it is desired to crank the engine in a direction opposite to that resulting from connecting the motor 120 therewith, the 30 main controlling lever 123 should be shifted to its extreme left-hand operative position, in which case the motor 121 will be connected up to the flywheel gearing, and a substantially duplicate set of circuit connections will be so effected as to give the required operations to the motor. Spring 137 35 will be effective, upon the release of member 123, to disconnect the motor 121 from the fly-wheel, and to restore member 123 40 to inoperative position.

While the form of mechanism herein shown and described constitutes a preferred form of embodiment of the invention, it is to be understood that other forms might be adopted, all coming within the scope of the 45 claims which follow.

What I claim is as follows:

1. In an engine starting system, the combination with a reversible engine; of a 50 plurality of starting motors normally at rest and disconnected from the engine; and a common controlling element operable to one position to connect one of said motors to the engine to crank the engine in one direction, 55 and to another position to connect another of said motors to the engine to crank said engine in a reverse direction; and means operable upon the release of the common controlling element for disconnecting one of 60 said motors from the engine, and to restore the controlling element to inoperative position, whereby the engine may run free of any connections with the starting motor.

2. In a starting system, the combination 65 with a reversible engine; of a starting device therefor, including a plurality of prime movers normally at rest and disconnected from the engine; a connecting unit associated with each of said prime movers; a source of power; connections between the source of power and the respective prime movers; and a common operating element operable to one position to actuate one of said connecting units, to connect the engine 70 and one of said prime movers together, and to close the connections between the power source and the said prime movers to crank the engine in one direction, and operable to another position to actuate another of the connecting units to connect another prime mover to the engine, and to close the connections between the power source and this other prime mover, whereby to crank 75 the engine in a reverse direction; and means operable upon the release of the common controlling element for disconnecting one of said motors from the engine, and to restore the controlling element to inoperative position, whereby the engine may run free of 80 any connections with the starting motor.

3. In an engine starting system, the combination with a reversible engine; of a plurality of electric motors normally at rest and disconnected from the engine; mechanical connections between said motors and the engine; a battery; circuit connections between the battery and motors; and a controlling member operable relative to said mechanical connections and said circuits, 95 whereby one of said motors may be connected to the engine to crank the same in one direction, and another of said motors may be connected to the engine to crank it in a reverse direction; and means operable 100 upon the release of the common controlling element for disconnecting one of said motors from the engine, and to restore the controlling element to inoperative position, whereby the engine may run free of any 105 connections with the starting motor.

4. In an engine starting system, the combination with a reversible engine; of a plurality of electric motors normally at rest and disconnected from the engine; normally 115 disconnectible mechanical connections between said motors and the engine; a battery; a set of circuit connections between each motor and the battery; and a common controlling member operable to one position 120 to effect the mechanical connection between one of said motors and the engine, and to close the set of circuit connections between said motors and the battery, to crank the engine in one direction, and to another position 125 to effect the mechanical connection between another motor and the engine and to close the set of circuit connections between

- that motor and the battery, whereby to crank the engine in a reverse direction; and means operable upon the release of the common controlling element for disconnecting 5 one of said motors from the engine, and to restore the controlling element to inoperative position, whereby the engine may run free of any connections with the starting motor.
- 10 5. In a starting system, the combination with a reversible engine; of a plurality of starting motors; and a common controlling element movable in a certain direction into a position whereby to effect the slow initial 15 movement of one of the motors and to effect the coupling up of one of the motors with the engine during the slow initial movement thereof, said element being movable further in the same direction to effect the 20 main cranking operation of the engine, and said controlling element being movable in the opposite direction to effect, first, the slow initial movement of the other motor and to effect the coupling up of the other 25 motor with the engine, and capable of movement in said opposite direction to a further

position whereby the main cranking operation of the said other motor may be effected.

6. In an engine starting system, the combination with a reversible engine; a plurality 30 of electric motors; mechanical connections between said motors and the engine; a battery; circuit connections between the battery and motors; a resistance element; and a controlling member operable relatively to the 35 mechanical connection and said circuit, whereby said controlling member may be moved in one direction, first, to connect the resistance element and one of the motors in series with the battery whereby the motor 40 may be connected with the engine during the slow initial movement thereof, and said controlling member being capable of movement in the opposite direction to effect the connection of said resistance unit and the 45 other of said starting motors in series with the battery, whereby said other motor may be connected with the engine during the slow initial movement thereof.

In testimony whereof I affix my signature. 50

WILLIAM A. CHRYSST.
